TOKEN THROWN GAME

John Armstrong, Bayonne, N. J.

Application June 25, 1947, Serial No. 756,937

2 Claims. (Cl. 273—105)

1

This invention relates to games, and more particularly such as are played with tokens thrown or pitched from a certain distance against obstructions.

The invention consists of a circular trap-like structure, having a central funnel below which a snap device is arranged to provide a snap-like noise on its return movement when a token moves it out of place, said snap device acting as a target. Concentrically surrounding the central target a table provided with numbered zones receives the tokens which missed the target. Preferably, the trap structure is constructed of wires forming spaces for the passage of the tokens, with suitable obstructions deflecting the tokens in order to add difficulties to the player. A bag below the table receives the tokens, both those which hit the target and those on the table, the table being provided with discharge means for ejecting the tokens into the bag.

In the accompanying drawings,

Fig. 1 is a central vertical section of the improved game;

Fig. 2 is a horizontal section taken on line 2—2 of Fig. 1, with the cage part removed;

Fig. 3 is a detail plan view of the snap target device, and fastening staple;

Fig. 4 is a detail side view of the pintle holding device;

Fig. 5 is a section on line 5—5 of Fig. 1, the wire being of metal surrounded by rubber;

Fig. 6 is a modified form of the wire shown in Fig. 5, the wire being of plastic;

Fig. 7 is a modified form of the vertical wire bent around the horizontal wires; and

Fig. 8 is a detail taken on line 8—8 of Fig. 2.

Similar characters of reference indicate corresponding parts throughout the various views.

Referring to the drawings, the structure preferably includes a square table 10 having legs 11.

Upon the upper surface of the table 10, a circular trap 12, consisting of a plurality of horizontally spaced barriers 13, held in spaced position by three or four vertically disposed wires 14. These vertical wires may be soldered to each horizontal barrier either to the inside or outside of the same, or may be looped around each of the same. These wires are preferably at the outside of the circular trap 12. Each of the horizontal barriers 13 is preferably shaped with a triangular cross-section, with one apex extending inwardly (Figs. 5—6). They may be made entirely of plastic or rubber, as in 15 in Fig. 6 or of a metallic rod 16 covered by a plastic or

2

rubber or a rubber composition as 17 in Fig. 5. By presenting the base outwardly, a better obstruction is provided against the entrance of small discs or tokens 31. The trap 12 has a central funnel 20, which terminates at its bottom at an opening 21 in the table 10. The lower end of this opening 21 is covered by a disc 22 of metal or the like, supported by a flat spring 25 held at 24. The tension of the spring 25 is balanced against the weight of a token, so that when a token rests on the disc 22, its weight will overcome the spring tension, and the disc 22 will descend, and the token will drop into the bag 27. On the return of the disc 22 under the reaction of the spring 25, it will cause a snapping noise.

The bag 27 may be of any suitable shape, but in the embodiment shown it is preferably of square shape, the body of the bag being of suitable textile material, and having a circumferential hem 28, in which a wire 29 is enclosed. This hemmed wire is suitably supported at the under surface of the table 10, by detachable supports 30, preferably of a turn-button type pivoted at 30a, enabling the bag to be removed or readily re-attached.

Upon the upper surface of the table, suitable markings are provided, as for instance, ten circles, numbered from one to ten, the highest number being nearest the central opening 21. As the tokens 31 of one color, take a position, on the upper surface of the table, the aggregate of the additions count in favor of that colored token, the other colored token, being also counted. The token which lists the target that is, the opening 21, receives the highest number.

When the number of tokens allowed to each player has been played, and the respective tokens are disposed on the upper surface of the table, and their positions counted, the game is completed, and it is necessary to gather the tokens for the next play.

For this purpose, the table 10, consists of two parts 10a and 10b, meeting at the center line of the table along the edges 33 of the table boards 10a and 10b, each part being hinged at their marginal ends, as by the hinges 35. The boards 10a and 10b may then be brought down into an inclined position sufficient to slide the tokens off and into the bag 27. The pintles 36 of the hinges 35 are extended at one end and provided with a handle 37 to manipulate the boards 10a and 10b. The pintle 36 is provided with two U-shaped bends 36a which press against the lower surface of the table boards in order to raise them

and return them to horizontal position. A hook device 40 is secured to a projection 41 of the table 10, which engages the handle 37 to hold it in a position corresponding to the horizontal position of the table boards. By unhooking the device 40 the boards drop into inclined tilted position. The other end of the pintle 36 is guided in a guide 42 screwed to the underside of the table 10.

Upon the upper surface of the table 10 is a 10 circumferential guard 40a to catch any tokens which do not enter the trap.

Thus, a skilled player succeeds in dropping the token into the central funnel and upon the spring actuated target disc 22, obtaining the highest mark. The other tokens are either obstructed by hitting the barriers and may drop into the circumferential guard 40, or are partially obstructed and fall within the embrasure of the trap, and take a position upon the upper surface of the table.

The shape of the trap device, is like that of dropped ogive, used as a generatrix. The wires, and by wire is included a plastic material, are arranged in spaced relationship, with the other wires decreasing in diameter from the lowest wire to the uppermost wire, and the inner wires increasing in diameter from the lowermost to the uppermost wire. These horizontally disposed wires are held in spaced position by suitable verticals by soldering or by looping. The spaces have a width slightly less than the diameter of a token, so that should the token arrive adjacent the wires in broadside position, the token will strike one or the other wire forming a space and be spun or deflected from its course. Should the token strike an inclined wall it will be deflected. Thus, many hazards are provided, which the skill of a player must overcome in order to obtain high markings or a target hit.

From the foregoing it is seen that the trap is formed of spaced horizontal triangularly shaped wires, with their apices directed inwardly, and their bases directed outwardly, the trap being circular in shape, and having a central funnel, below which the target is placed. This trap is supported on a table having graduated markings. Below the table is a bag to collect the tokens which have been played. The table is arranged to discharge the played tokens into the bag, which is detachable and replaceable.

The game can be played by one or four players in a home. Each player is allowed ten tokens of one color. The colors can be blue, green, red, yellow, which makes forty tokens.

When played at State fairs, benefit shows, etc., the concessionaire can have one person play the game for prizes such as cigars, dolls, canes, and such with suitable tokens.

To win the grand prize, the player must make a direct hit in funnel, causing the target to snap back with a smack.

I have described several forms of my invention, but obviously various changes may be made in the details disclosed without departing from the spirit of the invention as set out in the following claims.

I claim:

1. In a game, a plurality of horizontally disposed rings of wire vertically spaced apart, said plurality including outer rings decreasing in diameter from the lowest to the highest and including inner rings increasing in diameter from the lowest to the highest, a plurality of radially disposed pairs of hoops of wire of ogive shape having their inner ends spaced apart, to form a funnel shaped passage, supporting said inner rings and having their outer ends supporting said outer rings, said spacing of the wires providing passages for thrown tokens, a horizontal table for supporting the hoops, and having an opening below the funnel shaped passage, a spring actuated flap for closing the opening at the lower side of the table, said table having markings at its upper side radially disposed from said opening to the outer ends of the hoops, whereby a token striking the flap at the bottom of the funnel moves the flap and passes through the opening, and other tokens take a position on the upper side of the table along one of said markings.
2. The structure of claim 1, in which the table consists of a stationary frame and two parts hinged to said frame, the free ends of the parts meeting on a line passing horizontally through the opening, each part having a length at least substantially equal to the diameter of said outer ends of the hoops, and a width from its free end to its hinged end substantially equal to the radius of said outer ends of the hoops, the descending of the free end of the parts discharging the tokens from the upper side of the hinged parts of the table.

JOHN ARMSTRONG.
